Patented Mar. 6, 1900.

F. WANGELIN.
FLUSHING APPARATUS FOR WATER CLOSETS, &c.

(Application filed June 30, 1897.)

(No Model.)

UNITED STATES PATENT OFFICE.

FRIEDRICH WANGELIN, OF DRESDEN, GERMANY.

FLUSHING APPARATUS FOR WATER-CLOSETS; &c.

SPECIFICATION forming part of Letters Patent No. 644,882, dated March 6, 1900.

Application filed June 30, 1897. Serial No. 643,024. (No model.)

To all whom it may concern:

Be it known that I, FRIEDRICH WANGELIN, a subject of the King of Saxony, residing at Dresden, Germany, have invented certain new and useful Improvements in Flushing Apparatus for Water-Closets, (for which I have obtained Letters Patent in Germany, No. 92,896, dated April 30, 1896; in Austria, No. 46,220, dated June 2, 1896; in Hungary, No. 6,850, dated May 18, 1896; in Switzerland, No. 12,499, dated May 13, 1896; in France, No. 256,391, dated May 16, 1896; in Belgium, No. 121,416, dated May 18, 1896, and in Great Britain, No. 10,139, dated May 12, 1896,) of which the following is a full, clear, and exact description.

The present invention relates to a flushing device for water-closets and the like, and has for its object to bring about an efficient flushing by suddenly discharging the whole mass of water by upsetting the collecting-tank, the inlet-valve being closed gradually and without shock. For this purpose there is pivoted in a fixed tank a second trough-like tank, which when filled to a certain point becomes top-heavy and overturns. When the apparatus is next used, this pivoted tank is raised by means of a device operated by hand or connected with the seat from its overturned 25 vertical position into its horizontal position for the purpose of being filled again, the closing-lever of the inlet-valve being at the same time turned so that the latter is opened. As soon as the level of water in the inner pivoted 30 tank rises to a certain height this tank becomes top-heavy and is again overturned. During the filling of the tank a vessel attached to one arm of the valve-closing lever is also filled with water, and thus becomes 35 heavier than the balance-weight on the other arm of the lever. The contents of this vessel are, however, gradually discharged through a small opening, and owing to its slowly-decreasing weight the balance-weight gradually 40 sinks, so that the balance-lever turns very slowly and the valve is closed, not suddenly, but softly and without any shock. Both tanks, as well as the vessel, remain empty when not 45 in use, so that the apparatus cannot be damaged by frost.

In the accompanying drawings, Figure 1 shows, by way of example, one construction

of the device according to the present invention in longitudinal section, Fig. 2 in plan; and Fig. 3 in cross-section. The inner pivoted tank is in the position occupied when it has opened the valve by raising the balance-weight and turning the closing-lever. The dotted lines in Fig. 3 show the tank in its overturned position. Figs. 4 and 5 are perspective views, partly in section, of the whole apparatus, together with the disengaging device operated from the seat, Fig. 4 showing the tilting tank raised, as during the filling operation, and Fig. 5 showing it overturned. Fig. 6 is a detail of a ratchet device for the operating-lever.

In the outer tank *b*, provided with a discharge-pipe *a*, there is supported on pivots *c* a tank *d*, which in its overturned position is prevented by a spring *e* from oscillating. The inlet-valve *f* is opened and closed by means of a hinged finger *g* on a double-armed lever *g*. To the latter there is attached at one end a hollow vessel *h*, having a narrow opening or perforation *h'* in the bottom, and at the other end a balance-weight *k*, whose adjustable arm or stud *i* engages with the edge of the tilting tank *d*.

By depressing the movable seat or by pulling by hand the tilting tank *d* is brought, by means of a cord or otherwise, from the position of rest seen in dotted lines, Fig. 3, and in full lines, Fig. 5, into the horizontal position, Figs. 1 and 4, and by striking its edge against the arm *i* raises the balance-weight *k* and turns the lever *g*, which thereupon opens the inlet-valve *f*. When the water admitted has risen in the tank *d* so high that the vessel *h* is completely filled, the limit of filling the tank *d* is also reached, and the latter, owing to its peculiar trough-like shape, becomes top-heavy and overturns, the whole of its contents being discharged into the outer vessel *b* and into the discharge-pipe *a*. The vessel *h* is emptied during this time through its perforated base, and as the weight of this vessel *h* decreases so the balance-weight *k* sinks and slowly brings the lever *g* into the closing position for the inlet-valve.

The tank *d* remains in the upturned position until it is brought into a horizontal position, as by hand or automatically from the seat. Figs. 4 and 5 show such an automatic

raising device, which consists of a lever-frame *l*, preferably pivoted on the brackets of the seat, and a lever *n*, provided with a movable bell-crank lever *m*, to which lever *n* is attached, the lower end of the chain, cord, or the like *o* depending from the tank *d*.

When not in use, the back part of the frame *l* is kept down by weights *p*, secured to it, the upper part *q* projecting upward, in consequence of which the closet-seat, which is usually pivoted, is slightly raised. By depressing the seat the frame *l* swings upward, passing the lever *m*, which is movable upward and remains at the top during the time that the seat is depressed. As soon, however, as it is released the frame *l* again falls downward, striking the upper arm of the lever *m*, which is not movable downward, and depresses it and the lever *n*, connected to it, so that the tank *d* is brought by the cord *o* into its horizontal position and filling takes place.

Instead of the pivoted lever *n* any other equivalent device may be used.

To prevent the valve *f* from prematurely closing, there is arranged on one side wall of the outer tank *b* a ratchet device *r*, Fig. 6, in such manner that its toothed face holds the operative lever *g* in the "open" position which it is caused to occupy by the rising of the tilting tank *d* until this ratchet device *r* is released by the tank *d* striking in overturning against the projection *r'*, Fig. 6, dotted. In a similar manner the valve *f* may be prevented from opening too early by means of a correspondingly-acting device.

I claim—

1. The combination with a tank, and a discharge therefor, of a vessel pivotally mounted within the tank and adapted to overturn when filled with water to a certain height, a pivoted lever, a vessel carried thereby, pipes adapted to discharge water into the vessel carried by the lever and into the tank, a valve controlling the flow of water through said pipes, said valve being operated by the lever when the latter is tilted in one direction, the said lever being adapted to be operated by the pivoted vessel when the latter is turned to bring it to a horizontal position to effect the opening of the valve, all as and for the purpose specified.

2. The combination with a tank, and a discharge therefor, of a vessel pivotally mounted within the tank and adapted to overturn when filled with water to a certain height, a pivoted lever, a vessel carried thereby, pipes adapted to discharge water into the vessel carried by the lever and into the tank, a valve controlling the flow of water through said pipes, said valve being adapted to be opened when the lever is tilted or swings in one direction and to be closed when it swings in the reverse direction, said lever being engaged by the pivoted vessel when the latter is turned to bring it to a horizontal position to effect the opening of the valve, and being freed from the said vessel when the latter overturns to effect the closing of the valve.

3. The combination with a tank, and a discharge therefor, of a vessel pivotally mounted within the tank, and adapted to overturn when filled with water to a certain height, a pivoted lever, a vessel carried by one end of said lever, a weight carried by the other end of the lever, pipes adapted to discharge water into the latter-mentioned vessel and into the tank, a valve controlling the flow of water through the pipes, said valve being operated by the lever in its tilting movements, and said lever being adapted to be engaged by the pivoted vessel when the latter is turned up to a horizontal position.

4. The combination with a tank, and a discharge therefor, of a vessel pivotally mounted within the tank and adapted to overturn when filled with water to a certain height, a pivoted lever, a vessel carried thereby, pipes adapted to discharge water into the latter vessel and into the tank, a valve controlling the flow of water through the pipes, said valve being operated by the lever in its tilting movements, and a ratchet device within the tank engaging the pivoted lever and holding the same until the pivoted vessel has overturned.

5. The combination with a tank, and a discharge therefor, of a vessel pivotally mounted within the tank and adapted to overturn when filled with water to a certain height, a pivoted lever, a vessel carried thereby, pipes adapted to discharge water into the latter vessel and into the tank, a valve controlling the flow of water through the pipes, said valve being operated by the lever in its tilting movements, a ratchet device pivotally mounted within the tank with the teeth of which the pivoted lever is adapted to engage to prevent tilting of said lever in a direction to effect the closing of the valve, and said ratchet device being adapted to be operated by the pivoted vessel when the latter overturns to permit the said tilting movement of the lever.

6. The combination with a tank and a discharge therefor, of a vessel pivotally mounted within the tank and adapted to overturn when filled with water to a certain height, a pivoted lever, a vessel carried thereby, pipes adapted to discharge water into the vessel carried by the lever and into the tank, a valve controlling the flow of water through said pipes, said valve being operated by the lever in its tilting movements, the said lever being adapted to be operated by the pivoted vessel when the latter is turned to bring it to a horizontal position to effect the opening of the valve, and means for automatically bringing the pivoted vessel to a horizontal position comprising a pivoted seat and connections intermediate the latter and the pivoted vessel whereby when the seat is raised the pivoted vessel is brought to a horizontal position for filling.

7. The combination with a tank, and a discharge therefor, of a vessel pivotally mounted within the tank and adapted to overturn when filled with water to a certain height, a pivoted lever, a vessel carried thereby, pipes adapted

to discharge water into the vessel carried by the lever and into the tank, a valve controlling the flow of water through said pipes, said valve being operated by the lever in its tilting movements, and said lever being adapted to be operated by the pivoted vessel when the latter is turned to bring it to a horizontal position to effect the opening of the valve, and means for automatically bringing the vessel to a horizontal position consisting of a pivoted frame *l*, a pivoted seat operating said

frame, pivoted levers *m*, *n*, and a cord *o*, connecting the lever *n*, with the pivoted vessel, all arranged as and for the purpose specified.

In witness whereof I have hereto set my hand in the presence of the two subscribing witnesses.

FRIEDRICH WANGELIN.
